UNITED STATES PATENT OFFICE.

ADOLPH PETELEER, OF NEW YORK, N. Y.

AUTOMOBILE LIFTING-JACK.

1,214,710.

Specification of Letters Patent.

Patented Feb. 6, 1917.

Application filed March 8, 1916. Serial No. 82,796.

To all whom it may concern:

Be it known that I, ADOLPH PETELEER, a citizen of the United States, of 249 Centre street, New York, county of New York and State of New York, have invented certain new and useful Improvements in Automobile Lifting-Jacks, fully described and represented in the following specification and the accompanying drawings, forming a part of the same.

This invention relates to an improved construction of lifting jack possessing novel mechanism for the control of the lifting pawl and the supporting detent during the operations of raising and lowering the lifter-bar by the hand-lever, or raising or lowering the lifter-bar directly by hand to adjust it quickly into any desired position.

A round lifter-bar may be used in the present construction with circular rack-teeth formed thereon, or a square lifter-bar may be used with rack-teeth upon one edge only; but in either construction the pawl and detent are provided each with a pin projected from one side of the casing through a plate upon the casing, upon which plate cams are movable to operate upon the pins and control the movements of the pawl and detent as desired.

The cams are formed upon cam-bodies which are movable upon the outer surface of the plate, and the cam-bodies are pressed by springs to press the cams upon the pins, and means is provided to retract the cam-bodies in opposition to the pressure of such springs, and hold the cams in an inoperative position.

The casing of the jack is formed with a box through which the lifter-bar is extended, guides for the bar being formed in the casing at the upper and lower edges of the box. The box is preferably open at one side to insert the detent and the hand-lever socket, each of which has its inner end journaled in the rear side of the box, and its outer end journaled in a journal-plate which is applied to cover the open side of the box.

The cams and all their attachments are mounted upon the outer side of the journal-plate and can thus be secured thereto and adjusted in their operative position, so that the mere attachment of the journal-plate to the casing brings such parts into their operative relation to the pins of the pawl and detent. A cover is provided to in-

close all the parts attached to the journal-plate.

The invention includes various details of construction which will be understood by reference to the annexed drawing, in which—

Figure 1 is a side elevation of the jack with the cover removed to expose the journal-plate and its attachments; Fig. 2 is a side elevation of the head of the jack with both the cover and the journal-plate removed; Fig. 3 is a plan in section on line 3—3 in Fig. 1; Fig. 4 is a side elevation of the detent; Fig. 5 is a side view of the pawl; and Fig. 6 is a side view of the lifter-foot and its carrier, the carrier being broken for want of room upon the drawing. Fig. 7 is a plan in section on line 7—7 in Fig. 1. Figs. 8, 9 and 10 are diagrams showing various arrangements of the cam during different operations of the jack, Fig. 8 showing the detent-cam operating to hold the detent from the teeth of the lifter-bar; Fig. 9 showing the pawl-cam operating to hold the pawl from the teeth of the lifter-bar; and Fig. 10, showing both cams held in an inoperative position, so that the pawl when operated by the hand-lever may be free to raise the lifter-bar in the usual manner. Fig. 11 is a side view, and Fig. 12 an edge view of the pawl-cam and the body, shown in Fig. 1. Fig. 13 is an edge view of the jack; Fig. 14 an outer view of the cover N for the journal-plate E, and Fig. 15 is an elevation of the cam fixtures applied to a pawl and detent at the same side of a rack-bar.

In Fig. 1, the casing of the jack is shown with a box B adjacent to the top and having a column A extended below the box and provided with a base B', and the column extended at A' above the box to form a guide for the lifter-bar C. Cylindrical guides C' are shown in the column above and below the box, and the lifter-bar is made round and provided with annular sloping teeth C² and with a lifting-head C³. A hand-lever socket D is furnished with journals at opposite sides fitted respectively to a bearing D' in the rear side of the box B and to a bearing D² in the journal-plate E secured upon the front of the box, being thus hinged upon the casing, of which the plate E forms a part.

The plate is secured by screws E' to lugs

- E^2 which are projected inward from the walls of the box, and the plate is formed with rounded ears which are fitted to milled seats E^3 projecting from the lugs, so that 5 the plate is firmly supported to sustain the load imposed upon it by the journals of the detent and hand-lever socket, and the screws are relieved entirely of the load by the contact of the ears with the milled seats.
- 10 A pawl F is journaled upon the inner end of the hand-lever socket by a pivot d^6 so that the oscillation of the socket by a suitable handle D^3 (secured therein by a bayonet-lock d^2 , see Fig. 3) raises and lowers the 15 pawl to lift the lifter-bar. A detent G , for supporting the bar when lifted, is provided with journals at the opposite sides of its lower end, one of which is fitted to a bearing G' in the rear side of the box and the 20 other to a bearing C^2 in the journal-plate E . Pins a and a' are projected from the outer edges respectively of the pawl and detent and extended through the journal-plate, far enough to engage the sloping surfaces 25 of the cams c and c' .

The two cams are formed respectively at the upper ends of two parallel bodies d and d' , which are held movably upon the outer side of the journal-plate by screws or rivets 30 e inserted through slots e' in the cam-bodies, so as to be movable vertically.

The cam-surfaces are sloped outwardly from their upper ends, and the pins a and a' touch the upper ends of these cam-surfaces, 35 when the head of the pawl is raised by the hand-lever socket D to a level with the head of the detent, as shown in Figs. 1 and 2. The pawl and detent are pressed normally toward the lifter-bar by a spring b attached 40 at opposite ends to the pins a and a' , which spring is shown in Figs. 2 and 3 only, as its presence would confuse the other figures.

A recess H extends downward from the box upon the open side of the same, and the 45 cam-bodies have shanks d^2 projected downwardly through a foot-plate f which is fitted to the recess H to support springs g , g' fitted each between the foot-plate and one of the cam-bodies. These springs press the cam-bodies normally upward, and such upward 50 movement operates to press the upper corner of the cam c' against the pin a' , exerting a spring tendency to retract the detent from the teeth of the lifter-bar. Such tendency 55 produces no effect so long as the load upon the lifter-bar rests upon the detent, as is represented in Fig. 1, but the moment that the load is lifted by the pawl the cam rises and pushes the detent outward as shown in 60 Fig. 8. The spring under the cam-body d' is shown compressed in Fig. 1, as when the cam is held from movement by the load upon the detent.

The cam c is shown in Fig. 1 raised to its 65 full height by the spring upon its shank, in

which position the pawl, if carrying the load, forces the cam downward as the pawl descends, when moved downwardly by the hand-lever socket.

The two cam-bodies are provided with opposed shoulders o , and the cam-body d is provided with a cross-piece h upon which a manually operated cam i is arranged to bear. This manual cam is pivoted upon the journal-plate E by a screw j , and has a handle k by which it may be turned into its idle position shown in Fig. 1, or into its effective position shown in Fig. 10. In Fig. 1, the position of this manual cam permits the cam-body d to rise freely under the influence of the spring g' , but the turning of the cam i into its effective position, as shown in Fig. 10, pushes the cam-body d downward, and by the engagement of the shoulders o , as shown in Fig. 10, also holds the cam-body d from rising. Both cams are thus held in an inoperative position; which leaves the pawl and detent free, as shown in Fig. 10, for the operator to raise the lifter-bar in the normal manner, by a mere oscillation of the 90 hand-lever.

The springs g and g' are made of such strength that they are able to raise their respective cam-bodies and push the pawl or detent outwardly, in opposition to the 95 spring b when no load rests upon the pawl or detent.

In lowering the lifter-bar with a load, the pawl F is lowered, which has the effect of pushing the cam c downward until the 100 load is caught by the detent. When the load wholly rests upon the detent, the pawl is free and the upward pressure of the cam c moves the pawl outward, thus disengaging it from the tooth last lowered and permitting it to be raised to engage the tooth above. In such upward movement of the pawl, the cam c remains stationary, as its sloping surface permits the pin a to move 105 inward as the pawl enters the space above the tooth last engaged. When the pawl engages the succeeding tooth, the operator lifts the load slightly by such pawl to disengage the detent, and the detent is then immediately pushed outward by the automatic lifting of 110 its cam c' . Such action of the cam c' is shown in Fig. 8, the rising of the cam-body d' bringing the shoulders o in contact with one another as shown in that figure. The detent being clear from the teeth, the pawl 115 is then lowered with the load and pushes the cam c downwardly also carrying down with it the cam c' , as shown in Fig. 10, thus permitting the detent to engage a subsequent tooth. When the load again rests upon the 120 detent the pawl is relieved of its load and is cleared from the teeth by the automatic rising of its cam c . This permits the pawl to 125 be lifted again to engage and lower another tooth, as already described. To raise and 130

lower the lifter-bar freely by hand, the hand-lever is depressed, thus lifting the pawl sufficiently to release the detent from its load. When this is done the cam c' automatically rises and draws the detent out from the lifter-bar, as shown in Fig. 8. The weight of the lifter-bar is insufficient to oppose the action of the spring g' upon the cam c , and when the pawl is then lowered the cam c remains in its elevated position and operates to retract it from the lifter-bar, which permits the lifter-bar to drop automatically and leaves the bar entirely free to be raised and lowered by hand. A hanging-bar I is attached to the lifting-head C^3 to carry a lifter-foot. This hanging-bar extends downward by the side of the box B , upon which it is guided by lugs J . A foot K is provided with a flange K' having studs L attached thereto to engage slots M in the face of the hanging-bar. This construction permits the foot to be engaged with the hanging-bar at various distances from the lifting-head C^3 to fit beneath any object which it is desired to raise. Substantially the same cam mechanism is applicable to a lifter-bar toothed upon one side only, so that the pawl and detent are both applied to one side. Such a construction is shown in Fig. 15, where the lifter-bar C^4 is provided with teeth c^2 upon one side only, and the pawl F' and detent G^3 are fitted to the teeth upon the bar one above the other. The bar is covered by a plate C^5 which would serve as a journal-plate if extended over the pivot d^6 of the hand-lever socket and the pivot g^3 of the detent. The cam-bodies d^4 and d^5 are mounted parallel with one another upon the plate C^5 and movable vertically and provided with springs g^4 and g^5 resting upon a foot-plate f' . The relation of these parts will be understood from the description of the previous figures.

The pawl F' has a pin a^2 projected from it to engage a cam e^2 carried by the cam-body d^4 , and the detent G^3 has a pin a^3 projected from it to engage the cam e^3 upon the cam-body d^5 . The cam-body d^4 is provided with a seat or cross-piece h' and a manually operated cam l operates to depress the same when the handle h' is raised. All these parts operate precisely the same as in the construction of Fig. 1, so that the language of claim 1 describes the two constructions equally.

The construction of the jack is very advantageous, as it locates upon the outer side of the casing all the cam mechanism which operates upon the pawl and detent, while such mechanism is entirely protected from injury by the cover N . Such location for the cam mechanism is attained by the use of the journal-plate E to form the outer side of the box B , and the projection of the pins a and a' through, and from the outer

side of, such plate to be engaged by the cams c and c' . This disposition of the cams upon the outer side of the journal-plate renders the mechanism within the box more compact and the box itself relatively small in comparison with the body or column of the jack, and permits examination and repairs of the cam mechanism with the utmost facility. The journal-plate also serves as a foundation upon which all the cam mechanism is assembled and adjusted before the plate is applied to the body of the jack. This compactness is also promoted by locating the spring b inside of the journal-plate, where it does not occupy any useful space.

Having thus set forth the nature of the invention what is claimed herein is:

1. In a lifting jack, the combination, with a casing and a toothed lifter-bar, of a detent hinged upon the casing to engage the teeth of the bar, and a hand-lever socket hinged upon the casing with a pawl pivoted thereon to engage the teeth of the bar, means to press the detent and the pawl normally into the said teeth, pins projected respectively from the detent and the pawl at one side of the casing, and cams movable contiguous to the pins and having springs operating normally to press the cams upon the pins to retract the pawl and detent from the teeth.

2. In a lifting jack, the combination, with a casing and a toothed lifter-bar, of a detent hinged upon the casing to engage the teeth of the bar, and a hand-lever socket hinged upon the casing with a pawl pivoted thereon to engage the teeth of the bar, means to press the detent and the pawl normally into the said teeth, pins projected respectively from the detent and the pawl at one side of the casing, cams movable contiguous to the pins, springs pressing the cams normally against the pins, and means for moving the cams to an inoperative position for the purpose set forth.

3. In a lifting jack, the combination, with a casing and a toothed lifter-bar, of a detent hinged upon the casing to engage the teeth of the bar, and a hand-lever socket hinged upon the casing with a pawl pivoted thereon to engage the teeth of the bar, means to press the detent and the pawl normally into the said teeth, pins projected respectively from the detent and the pawl at one side of the casing, cam-bodies movable parallel with one another between the said pins and having outwardly sloped cam-faces to press the pins apart, and springs operating upon the cam-bodies to press the cam-faces normally against the said pins.

4. In a lifting jack, the combination, with a casing having a box open upon one side and a lifter-bar movable vertically through the box, of a journal-plate secured on the

box, a hand-lever socket and a detent having journals at their opposite sides fitted respectively to the rear side of the box and the journal-plate, a pawl pivoted upon the hand-lever socket to engage the teeth of the lifter-bar, pins projected respectively from the detent and the pawl through the said journal-plate, cams mounted to move upon the journal-plate in contact with the pins, and means for pressing the cams normally toward the pins.

5. In a lifting jack, the combination, with a casing having a box open upon one side and a lifter-bar movable vertically through the box, of a hand-lever socket pivoted on the casing, a pawl pivoted upon the hand-lever socket to engage the teeth of the bar, a journal-plate secured upon the open side of the box, a detent hinged upon the casing to engage the teeth of the bar, means to press the detent and pawl normally into the said teeth, pins projected respectively from the detent and the pawl through the said journal-plate, cams mounted to move upon the journal-plate in contact with the pins, and springs for pressing the cams normally toward the said pins.

6. In a lifting jack, the combination, with a casing having a box open upon one side and a lifter-bar movable vertically through the box, of a hand-lever socket pivoted on the casing, a pawl pivoted upon the hand-lever socket to engage the teeth of the bar, a journal-plate secured upon the open side of the box, a detent hinged upon the casing to engage the teeth of the bar, means to press the detent and pawl normally into the said teeth, pins projected respectively from the detent and the pawl through the said journal-plate, cams mounted to move upon the journal-plate in contact with the pins, springs for pressing the cams normally toward the said pins, and a manually operated cam movable on the journal-plate to move the cam-bodies to an inoperative position.

7. In a lifting jack, the combination, with a casing having a box open upon one side and a lifter-bar movable vertically through the box, of a hand-lever socket journaled in one edge of the box with a pawl pivoted thereon, a journal-plate secured upon the open side of the box, a detent hinged upon the casing to engage the teeth of the bar, means to press the detent and pawl normally into the said teeth, pins projected respectively from the detent and the pawl through the said journal-plate, cam-bodies movable upon the journal-plate parallel with one another and having outwardly sloping cam-faces to press the pins apart, springs pressing the cam-bodies longitudinally to press the cam-faces normally against the said pins, and means for retracting the cam-bodies in opposition to the said springs.

8. In a lifting jack, the combination, with

a casing having a box open upon one side, of cylindrical guides in the casing at the top and bottom of the box, a cylindrical toothed lifter-bar fitted to such guides, a journal-plate secured upon the open side of the box, a detent journaled upon the box and journal-plate, a hand-lever socket journaled upon the box and journal-plate, a pawl pivoted upon the hand-lever socket to engage the teeth of the bar, pins projected respectively from the detent and pawl through the said journal-plate, cam-bodies movable upon the journal-plate, and cams carried by such bodies, with springs to move the cams automatically toward the pins, and operating to retract the pawl or the detent when the same is free from load.

9. In a lifting jack, the combination, with a casing having a box open upon one side with guides in the casing above and below the box and a toothed lifter-bar fitted to such guides, of a lifter-bar movable vertically through the guides, lugs projected inwardly from the edges of the box adjacent to the open side with circular seats upon such lugs next the wall of the box, a journal-plate fitted to the lugs and having rounded ears fitted to the seats, a detent pivoted upon the rear side of the box and the journal-plate, and a hand-lever socket pivoted upon the rear side of the box and the journal plate, with a pawl carried by the hand-lever socket for raising and lowering the lifter-bar.

10. In a lifting jack, the combination, with a casing having a box open upon one side, and a lifter-bar movable vertically through the box, of a journal-plate secured upon the open side of the box, a hand-lever socket and a detent having journals at their opposite sides fitted respectively to the rear side of the box and the journal-plate, a pawl pivoted upon the hand-lever socket to engage the teeth of the lifter-bar, means to press the detent and pawl normally into the said teeth, pins projected from the detent and pawl through the said journal-plate, cam-bodies fitted movably upon the journal-plate and having respectively cams to operate upon the pins of the detent and pawl, the cam-bodies being parallel with one another and slotted longitudinally and secured upon the journal-plate by rivets inserted through the slots, and a foot-plate with springs inserted between the foot-plate and the cam-bodies, pressing the cams normally toward the said pins.

11. In a lifting jack, the combination, with a casing having a box open upon one side, a toothed lifter-bar movable through the box, of a journal-plate secured upon the open side of the box, a detent and a hand-lever socket journaled upon the rear side of the box and upon the journal-plate, with a pawl pivoted upon the hand-lever socket,

pins projected respectively from the detent and the pawl through the journal-plate, two cam-bodies fitted to move vertically upon the journal-plate and having cams to operate respectively upon the said pins, and having downwardly extending shanks with springs fitted thereto, the casing having a recess extended downward from the box to receive the said shanks and springs, and the recess having a foot-plate therein to sustain the springs.

12. In a lifting jack, the combination, with a casing having a box open at one side with guides in the casing above and below the box and a toothed lifter-bar fitted to such guides, of a lifter-bar movable vertically through the guides, lugs projected in-

wardly from the edges of the box adjacent to the open side with seats upon such lugs to engage the journal-plate, a journal-plate fitted to the lugs and having ears fitted to the said seats, means for fastening the ears to the lugs, a detent pivoted upon the rear side of the box and journal-plate, a hand-lever socket pivoted upon the rear side of the box and the journal-plate, with a pawl carried by the hand-lever socket, the fastenings of the journal-plate being wholly relieved from the strain of the detent and hand-lever socket by the engagement of the journal-plate with the seats upon the lugs.

15. In testimony whereof I have hereunto set my hand.

ADOLPH PETELER.
